UNITED STATES PATENT OFFICE.

THOMAS FLEMING, OF CLEVELAND, OHIO, ASSIGNOR OF ONE-HALF TO
FRANK C. CARROL, OF CLEVELAND, OHIO.

TRANSFER-TRUCK.

SPECIFICATION forming part of Letters Patent No. 768,275, dated August 23, 1904.

Application filed December 23, 1903. Serial No. 186,394. (No model.)

To all whom it may concern:

Be it known that I, THOMAS FLEMING, a citizen of the United States, residing at Cleveland, in the county of Cuyahoga and State of Ohio, have invented a certain new and useful Improvement in Transfer-Trucks, of which the following is a full, clear, and exact description, reference being had to the accompanying drawings.

10 This invention is an improvement upon the transfer-trucks that form the subject-matter of the application Serial No. 178,476, filed by F. C. Carroll and myself on October 26, 1903.

15 The object of this invention is to simplify and cheapen the construction shown in said prior application and to improve it by providing means for raising the truck-platform very rapidly.

20 In the drawings, Figure 1 is a side elevation of a transfer-truck embodying my invention. Fig. 2 is an end view thereof when the truck-platform is in its lowest position. Fig. 3 is an end view thereof when the truck-platform is in the highest position. Fig. 4 is an end 25 view of the platform-raising mechanism when the platform is lifted to an intermediate position, a portion of the lifting-eccentric being broken away in this view to show the means for holding the shaft against rotation in the 30 direction to lower the platform. Fig. 5 is a side elevation of the rear end of the truck when the platform is held in an intermediate position.

35 Referring to the parts by letters, A represents the running-gear of the truck, and B the truck - platform, having depending legs b, which operate in guide-recesses in the running-gear.

40 C represents a turn-table which is mounted upon the truck-platform and which supports the swinging platform D.

E represents the tray having wheels or rollers supported upon said swinging platform.

45 G represents a centrally-placed longitudinal shaft journaled in the running-gear and extending from one end thereof to the other, said shaft being located below the truck-plat-

form. To this shaft eccentrics H are secured, which eccentrics engage with friction-rollers b', carried by the truck-platform.

50 g represents a lever by means of which the shaft G may be turned. By so turning the shaft the eccentrics by their engagement with said friction - rollers lift the truck-platform and the parts carried thereby, said platform 55 being prevented from tipping out of a horizontal position during its upward or downward movement by the guide-legs on its under side and the guides in the running-gear with which they engage. The platform may be 60 raised to any intermediate height between the high and low limits and may be held in such intermediate position by means of a pawl K, pivoted to the running-gear, in engagement with a ratchet-wheel g' on the shaft G.

65 Having described my invention, I claim—

1. The combination with the running-gear, of a truck having vertical guides, and a vertically-movable truck - platform having legs engaging in said guides, of a shaft rotatably 70 mounted upon the running-gear, and eccentrics secured to said shaft for raising the truck-platform, friction-rollers carried by the truck-platform and bearing upon the peripheries of said eccentrics, substantially as and for the 75 purpose specified.

2. The combination with the running-gear of a truck having vertical guides, and a vertically-movable truck - platform having legs engaging in said guides, of a shaft rotatably 80 mounted upon the running-gear, eccentrics secured to said shaft for raising the truck-platform, a lever for operating the same, a ratchet-wheel secured to said shaft, and a pawl pivoted to the running-gear, substantially as and 85 for the purpose specified.

In testimony whereof I hereunto affix my signature in the presence of witnesses.

THOMAS FLEMING.
